UNITED STATES PATENT OFFICE.

CALVIN F. MOSS AND MICHAEL JUNGLING, OF BOGALUSA, LOUISIANA.

INTERNAL-COMBUSTION ENGINE.

1,111,605.

Specification of Letters Patent. Patented Sept. 22, 1914.

Application filed January 23, 1914. Serial No. 313,377.

To all whom it may concern:

Be it known that we, CALVIN F. Moss and MICHAEL JUNGLING, both citizens of the United States, residing at Bogalusa, in the parish of Washington and State of Louisiana, have invented new and useful Improvements in Internal-Combustion Engines, of which the following is a specification.

This invention relates to internal combustion engines, the object of the invention being to produce an engine of simple and economical construction which is reliable in operation, and which operates on the double action principle, the engine embodying a pair of oppositely arranged oscillatory pistons moving in an annular expansion chamber and both connected to a common crank shaft, the charges being admitted alternately at opposite ends of the pistons and being ignited so as to give an impulse to the pistons first in one direction and then in the opposite direction, two explosions thus taking place in each complete cycle of operation of the engine.

A further object of the invention is to provide simple and effective means mounted upon and actuated by the engine, serving to compress the charges and force the same into the combustion and expansion chambers; also to provide check valves between the compressing means and the compression chambers, combined with means for mechanically locking said check valves closed and unlocking the same at the proper periods.

With the above and other objects in view, the invention consists in the novel construction, combination and arrangement of parts, as will hereinafter be more fully described, illustrated and claimed.

In the accompanying drawings:—Figure 1 is a view partly in front elevation and partly in section of an engine embodying the present invention. Fig. 2 is a cross section through the same on the line 2—2 of Fig. 1. Fig. 3 is a detail elevation of the open center pitman which operates the charge compressing mechanism. Fig. 4 is an enlarged vertical transverse section on the line 4—4 of Fig. 2.

In the preferred embodiment of this invention, the engine comprises a stationary main frame plate 1 adjacent to the bottom of which is provided a bearing 2 for the crank shaft 3, said frame plate 1 being extended below the bearing 2 to form one of

the side walls 4 and bottom 5 of the crank case which, it will be observed, is offset to one side of the vertical plane of the housing in which the pistons hereinafter described operate, the crank shaft 3 being provided with the cranks 6 which are offset from each other as best illustrated in Fig. 1.

Secured fixedly to the main frame plate 1 is an annular housing 7 which, in cross section, is shown as substantially square, the said housing section 7 being three-sided as shown in Fig. 4 and being water jacketed at 8 so as to provide for the circulation of water throughout the walls of the expansion chamber in which the pistons operate. 9 designates a detachable crank case plate which is bolted or otherwise fastened as shown at 10 to the crank case and which is fastened as shown at 11 to the housing 7. This plate 5 is also formed with a bearing 12 for the crank shaft adjacent to that end upon which the fly-wheel 13 is mounted.

Mounted to oscillate in the opposite side portions of the annular expansion chamber 14 inclosed by the main frame plate 1 and the housing 7 are arcuate pistons 15 the form of which is best shown in Fig. 1. Located in the center of movement of the pistons 15 is a pair of concentric rock shafts 16 which have coincident axes of movement, one of said rock shafts 17 inclosing and being journaled upon the other rock shaft 18, the last named rock shaft passing axially through the rock shaft 17 and being journaled at one end in a bearing boss 19 on the inner surface of the crank case plate 9 as shown in Fig. 4. At its opposite end the shaft 18 bears against an end thrust plate 20 fastened as shown at 21 to the main frame plate 1, the tubular rock shaft 17 also bearing at its corresponding end against said end thrust plate 20. An additional bearing in the form of a collar 22 surrounds the shaft 18 and is fastened as shown at 23 to the rocker arm hereinafter referred to which is connected to the tubular rock shaft 17.

Piston arms 24 extend from the pistons 15 inwardly, one of said arms being rigidly connected to the rock shaft 18 and the other arm 24 being rigidly connected to the rock shaft 17. To one side of the vertical plane of the housing 7, rocker arms 25 extend from the shafts 17 and 18 in opposite directions as shown in Figs. 1 and 2 where they are pivotally attached at 26 to connecting rods 27, the said rods being con-

nected to the crank shaft as shown in Figs. 1 and 4.

Each of the pistons 15 is provided adjacent to its opposite ends with piston rings 28 conforming of course in cross section to the corresponding cross sectional shape of the pistons and each piston ring embodying a number of overlapping portions which are thrust outward by internal pressure, each piston being provided in each end with a number of pressure ports 29 through which the expanding gas is admitted to the under sides of the piston rings 28 for the purpose of forcing the sections thereof outwardly into close working contact with the inside walls of the expansion chamber.

At diametrically opposite points the main frame plate 1 is formed with openings 30 constituting combustion chambers and secured in fixed relation to the outer side of said frame plate 1 are casings 31 which are chambered as shown at 32 to form combustion chamber extensions through the wall of which are inserted igniters shown in the form of spark plugs 33. The compressed charges of gas are admitted through the combustion chambers 30 and the exhaust gases pass out through exhaust ports 34 in the main frame plate 1, shown in Fig. 1.

Each of the casings 31 comprises a charge compressing cylinder 35 in which is a reciprocating piston 36. The pistons 36 are arranged diametrically opposite each other as shown in Fig. 1 and are connected in rigid relation to each other by a common piston rod 37 to which is pivotally attached at 38 the upper extremity of a pitman 39 carrying at its lower end an eccentric strap 40 of two-part sectional construction as illustrated in Fig. 3, said strap 40 extending around an eccentric 41 revolving with the crank shaft 3 and being fastened thereon by means of a set screw 42 or equivalent means. The pitman 39 is of skeleton form or provided with an open center as indicated at 43 so that it will straddle the lower casing 31. Each of the cylinders 35 communicates with the combustion chamber 30 by means of a port 44 which is controlled by a check valve 45 seated in the outer end of the cylinder 35.

46 designates a pair of intake pipes leading from one or more carburetors to the engine and within each of said pipes 46 is arranged an automatic intake valve 47. A port 48 leads from the chamber of the valve 47 into the cylinder 35. It will thus be seen that as each piston 36 reciprocates, it sucks into the cylinder 35 a charge of gas and compresses the same and forces it into one of the combustion chambers of the engine.

In order to insure the check valve 45 remaining closed during an explosion, we provide a special check valve locking de-

vice illustrated in Fig. 4, said locking device consisting of a two-armed lever, one arm 49 of which is connected to the stem of the check valve 45 while the other arm 50 is movable into and out of a recess in the wall of the cylinder 35. The check valve is free to open and close throughout the major portions of both strokes of the adjacent piston 36. If, however, the piston approaches very closely to the check valve 45 as indicated in the lower cylinder 35 in Fig. 4, it engages the arm 50 of the valve lock so that the other arm 49 cannot move, thus holding the check valve 45 locked in closed position. This is to prevent any possibility of back fire from the combustion chamber into the charge compressing cylinders and intake pipes from the carburetor. Threaded plugs 51 give access to the several valves referred to for cleaning and repairing or renewing the same. Any suitable commutator or timer may be used for generating sparks in the plugs 33 at the proper intervals and water connections may be attached to the water jacket 8 at suitable points to provide for admitting water to and conducting the same off from said jacket.

From the foregoing description it will now be understood that the charges of explosive mixture are compressed and introduced alternately into the combustion chambers 30, the result being that the oscillatory pistons are driven first in one direction and then in the opposite direction, thus producing two power strokes or impulses in each complete cycle of operation of the engine. The expanding gas thus drives the pistons apart and at the opposite side of the casing the gases are exhausted through the ports 34 as the pistons reach the ends of their strokes. The inrushing fresh mixture assists in discharging the burnt gases and as the pistons start upon their return movement under the force of an explosion at the opposite ends thereof, the fresh charge of gas so admitted is compressed between the approaching ends of the pistons in a manner which will be readily understood. On account of the pistons 15 being arranged oppositely to each other, one balances the other and an engine is thus produced which operates smoothly and with a minimum amount of vibration. Furthermore the combined movement of the two pistons provides for a full and complete expansion of the gas the pressure of which is thereby reduced to such an extent that the noise of the exhaust upon reaching the outer atmosphere is very much reduced, making the engine quiet in operation. Any suitable means may be employed for properly lubricating the working parts of the engine.

What we claim is:

1. In an internal combustion engine, a

housing inclosing an annular expansion chamber, a main frame plate forming one side wall of said expansion chamber and provided with combustion chambers at 5 points where said pistons approach the nearest to each other, an igniter in each of said combustion chambers, arcuate pistons mounted for oscillatory movement therein about a common axis, rock shafts having co- 10 incident axes of movement and journaled one upon the other, arms connecting said pistons to their respective rock shafts, rocker arms on said shafts, a crank case, a crank shaft journaled therein, connecting rods ex- 15 tending from said rocker arms to said crank shaft, charge compressing means mounted on and driven by the engine and arranged to discharge the compressed charge into said combustion and expansion chambers, and 20 means preventing the return movement of said compressed charges.

2. In an internal combustion engine, a housing inclosing an annular expansion chamber, a main frame plate forming one 25 side wall of said expansion chamber and provided with combustion chambers at points where said pistons approach the near-

est to each other, an igniter in each of said combustion chambers, arcuate pistons mounted for oscillatory movement therein about a common axis, rock shafts having co- 30 incident axes of movement and journaled one upon the other, arms connecting said pistons to their respective rock shafts, rocker arms on said shafts, a crank case, a crank shaft journaled therein, connecting rods extending from said rocker arms to said crank shaft, charge compressing means mounted on and driven by the engine and arranged to discharge the compressed charge into said combustion and expansion chambers, means preventing the 35 return movement of said compressed charges, check valves between said compressing means and combustion chambers, 40 and mechanically controlled means for locking and unlocking said check valves.

In testimony whereof we affix our signatures in presence of two witnesses.

CALVIN F. MOSS.

MICHAEL JUNGLING.
